JAMES F. SMATHERS, OF KANSAS CITY, MISSOURI.

LINE-LOCK FOR TYPE-WRITING MACHINES.

1,215,586.

Specification of Letters Patent. Patented Feb. 13, 1917.

Application filed June 28, 1915. Serial No. 36,877.

To all whom it may concern:

Be it known that I, JAMES F. SMATHERS, a citizen of the United States, residing at Kansas City, in the county of Jackson and State of Missouri, have invented certain new and useful Improvements in Line-Locks for Type-Writing Machines, of which the following is a specification.

This invention relates to line locks for typewriting machines and my object is to produce a device of this character which makes it impossible to print a line of greater than a predetermined length or to "pile up" two or more characters at the same point when the end of the line is reached.

With this general object in view, the invention consists in certain novel and peculiar features of construction and organization as hereinafter described and claimed; and in order that it may be fully understood reference is to be had to the accompanying drawing, in which—

Figure 1, is a vertical section of a part of a typewriting machine taken on the line I—I of Fig. 2.

Fig. 2, is a vertical section taken on the line II—II of Fig. 1.

Fig. 3, is a fragmentary view showing the line lock device in normal position as distinguished from the showing of said device in Fig. 2 in which figure it is shown in operative position.

Fig. 4, is a fragmentary view of a modified form of the line lock device.

In the said drawing, 1 indicates a part of the frame of a typewriting machine, 2 the levers thereof, 3 the pivotal point for said levers, and 4 the pivot carrying cross bar. In the construction shown, the key levers are equipped with depending projections or heels 5, all of said heels being transversely alined.

The line locking device is constructed as follows:

6 is a bar arranged transversely within the frame and provided with trunnions or pivots 7, suitably journaled with respect to the frame below the key levers. The bar is provided for its full length with a V-shaped kerf 8, the lower end of the kerf being deflected to form a downwardly facing shoulder 9.

10 is a series of fingers arranged in said kerf, one below each key lever, and said fingers are provided with offset portions 11

at their lower ends which underlie the shoulder 9 and thus guard against upward bodily movement of the fingers within the kerf. The parts are so proportioned that the fingers are free to swing from a point forward of the plane of the heels of their overlying or respective key levers to a point vertically below such heels, it being also noticed by reference to Fig. 2, that when a finger occupies its rearward or operative position it will prevent downward movement of the key lever.

To hold the fingers pressed yieldingly rearward against the rear wall of the kerf, their normal position, I prefer to employ individual springs 12, which springs are preferably of right angle form as shown, and all project from an integral lower or channel portion 13 embracing the lower end and front and rear sides of the bar 6. A retractile spring 14 attached at one end to the frame as at 15, is connected to a short crank arm 16 of a collar secured on one of the trunnion ends or pivots, and connected to a similar crank arm 17 is a rearwardly extending rod 18, adapted as the carriage reaches the end of each line, to be moved rearward and swing the bar 6 from the position shown in Fig. 3, to the position shown in Fig. 2, in which latter position the fingers 10 are vertically below the heels 5 of all of the key levers which are in their elevated or normal positions. If at the time the bar is swung forward as explained, a lever is in a depressed position, its respective finger 10 will engage the front edge of the heel and as a result said finger will be relatively swung forward against the front wall of the kerf 8, and its respective spring 12 will be pressed forward as shown in Fig. 2, but will immediately force the displaced finger back into line with the other fingers as the said depressed key is returned to normal or elevated position. It will thus be seen that a depressed key cannot hold the line lock bar in inoperative position as is the case with that type of line lock mechanism consisting of a rigid or continuous bar incapable of being swung or moved to operative position below any of the key levers or heels thereof, if a single key lever happens to be depressed. Because of this fact line locks of the type described do not perform their prescribed function when the machine is being oper-

ated with considerable rapidity, as a rapid operation results in downward movement of one key lever before the previously depressed key lever reaches its normal or elevated position. In other words where a machine is operated rapidly there is always one or more keys in a depressed or partly depressed position and hence it is impossible for the line lock to perform its function when the predetermined end of the line has been reached if a single key lever is depressed. It is therefore obvious that letters may be printed beyond the point where the line should end or, if the carriage has ceased to move, that characters may be "piled up" at the end of the line, this piling up of characters being as unsightly as running occasional lines several characters beyond adjacent lines. With my line lock comprising a bar carrying individual fingers for the different key levers, it will be impossible to run a line too far or to pile up characters at the end of the line.

In Fig. 4, a modified construction is shown, the same comprising an oscillatory bar 6 provided with spring fingers 19, any one of which will yield upon encountering the heel of its respective key lever, as the bar is rocked toward its operative position, the said finger springing under the heel of its respective lever, immediately the latter is released and rises to normal position.

From the above description it will be apparent that I have produced a line lock which can be easily and cheaply secured to a typewriting machine, and which will perform its function efficiently and reliably as outlined in the statement of the object of the invention, and while I have illustrated and described a modified form as well as my preferred form, it is to be understood that I reserve the right to any construction which properly falls within the spirit and scope of the appended claims.

45 I claim:

1. The combination in a typewriting machine, of the key levers, a movable bar below the said levers, and fingers carried by said bar in the planes of movement of the respective levers, each finger being yieldingly controlled and when the bar is moved to operative position, caused to take a position below its respective lever or to engage and yield to the resistance offered by its respective lever if the latter is in its depressed position.

2. The combination in a typewriting machine, of the key levers, a movable bar below the said levers, fingers carried by said bar in the planes of movement of the respective levers, each finger being yieldingly controlled and when the bar is moved to operative position, caused to take a position below its respective lever or to engage and yield to the resistance offered by its respective lever if the latter is in its depressed position.

ver if the latter is in its depressed position, and means for returning the movable bar to its initial or inoperative position.

3. The combination in a typewriting machine, of the key levers, a movable bar below the said levers, fingers carried by said bar in the planes of movement of the respective levers, each finger being yieldingly controlled and when the bar is moved to operative position, caused to take a position below its respective lever or to engage and yield to the resistance offered by its respective lever if the latter is in its depressed position, and a spring for returning the movable bar to its initial or inoperative position.

4. The combination in a typewriting machine, of the key levers provided with depending heels, a suitably-journaled rock bar extending transversely of the machine, and provided with upwardly projecting fingers, a spring normally holding said rock bar with its fingers forward of the heels of the key levers, and means for applying yielding pressure on said fingers individually whereby any one of the fingers may yield upon encountering the heel of a depressed key lever, and resume its position in line with the other fingers when its respective key lever is reelevated.

5. In a typewriting machine, a line lock bar pivoted to rock about its longitudinal axis and provided along its length with upwardly projecting yieldingly controlled fingers, all of which stand in the same radial plane with relation to the axis of said bar and are capable of being individually sprung back out of the plane of the remaining fingers and of springing forwardly into said plane.

6. A line lock bar provided with a longitudinal kerf or groove of V-shape in cross section and having a downwardly facing shoulder at the bottom of the groove or kerf, a series of fingers arranged side by side along the length of and within said kerf or groove and capable of swinging movement from one wall of the groove to the other, and provided with bent portions underlying said shoulder, and springs pressing against all of the fingers and holding them normally against the same wall of the kerf or groove.

7. A line lock bar provided with a longitudinal kerf or groove of V-shape in cross section and having a downwardly facing shoulder at the bottom of the kerf or groove, a series of fingers arranged side by side along the length of and within said kerf or groove and capable of swinging movement from one wall of the groove to the other, and provided with bent portions underlying said shoulder, and a spring plate provided with a grooved lower portion embracing the sides and lower edge of the bar,

and provided with a series of right angle shaped springs fitting against one side and upon the upper edge of the bar; each spring bearing against one of the said fingers and adapted to yield to permit the finger to be swung forward upon encountering an unyielding obstruction.

8. The combination with a series of key levers of a line lock device comprising a bar 10 provided with a line of fingers for the respective key levers, means for adjusting said bar to shift said fingers from a position out of the path of operation of the key levers to a position in the path of operation of said 15 levers, each finger being yieldingly con-

trolled and adapted to be sprung out of line by its respective key lever if the same happens to be in its depressed position when the adjustment of said bar occurs and to spring back to normal position immediately 20 said lever is released and returned to normal position, and means to reverse the adjustment of said bar when the first-named means is inoperative.

In testimony whereof I affix my signature 25 in the presence of two witnesses.
